CENTRIFUGAL CASTING APPARATUS

Albert E. Moorhead, San Francisco, Calif.

Application November 8, 1937, Serial No. 173,324

16 Claims. (Cl. 25—41)

This invention relates to a system for casting articles from plastic material, such as hydraulic cement or concrete; and especially to apparatus utilizing centrifugal force for urging the material into the molds.

The advantages of centrifugal casting are well understood. Such casting has been proposed by feeding the material into the interior of a rotary drum, the molds being supported on the exterior of the drum and in communication therewith. After casting, the drum had to be stopped and the molds emptied one by one.

It is one of the objects of this invention to make it possible to discharge the molded articles even while the drum is rotating, and to manipulate the molds so that they may open and close during rotation.

It is another object of the invention to make it possible to assist the discharge of the cast articles by centrifugal force at any time desired by the operator, and preferably on a moving conveyor which carries them to a location where they may be stacked and cured.

It is another object of the invention to improve in general, centrifugal casting apparatus of the character under consideration.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a vertical sectional view partly broken away of the apparatus embodying the invention, and illustrating the mechanism for opening and closing the molds;

Fig. 2 is a view similar to Fig. 1, but illustrating the mechanism at the opposite end of the apparatus for opening and closing the gate closures for the molds;

Fig. 3 is a fragmentary horizontal sectional view of the rotary mechanism and its associated parts;

Fig. 4 is a detail sectional illustrating the cam mechanism utilized for opening and closing the molds;

Fig. 5 is a detail cross section of the cam track;

Fig. 6 is a sectional view taken substantially along plane 6—6 of Fig. 2;

Fig. 7 is a side elevation of one of the molds and its associated parts;

Fig. 8 is a sectional view taken along plane 5—8 of Fig. 7;

Fig. 9 is an end view of one of the molds taken along the plane 9—9 of Fig. 7;

Fig. 10 is a top plan view of one of the molds;

Fig. 11 is a sectional view taken along plane 10—11 of Fig. 7;

Fig. 12 is a view similar to Fig. 8, but showing the mold in open position; and

Fig. 13 is a pictorial view of an article cast in accordance with the present invention.

In the present instance the apparatus is illustrated as capable of molding the roof shingle 1 (Figs. 12 and 13), although other articles may be molded upon appropriate change in mold configuration.

The plastic materials, such as concrete or hydraulic cement, which are used for forming the article 1, can be fed to the interior of a rotary drum structure 2. This drum structure 2 is appropriately supported on a horizontal axis to rotate thereon. For example, the drum structure may include the end flanges 3 and 4 which may be formed of castings. These flanges serve to support the exterior cylindrical portion 5 of the drum as by any appropriate fastening means. This part 5 can be appropriately formed of sheet metal telescoping over the annular rims of the flanges 3 and 4.

Each of the end flanges 3 and 4 can be provided with a hollow tubular extension such as 6 and 7. These tubular extensions serve as trunnions for the drum, as well as a means of ingress of the plastic material.

The manner in which the extensions 6 and 7 are rotatably supported is best explained in connection with Figs. 2 and 3.

In these figures it is seen that a standard 8 is provided, which is bolted to the supporting base 9. This standard has a circular channel 10 which serves to accommodate the rollers 11. These rollers are freely rotatable on the pivot bolts 12 which pass across the channel 10. As shown most clearly in Fig. 2, the extensions 6 and 7 can be provided with a periphery contacting with rollers 11, said periphery having a series of projections 13. These projections pass over the rollers 11, causing considerable vibration to be imparted to the drum structure during the period of rotation, whereby the plastic material inside of the drum is vibrated so as to render

the material dense and uniform in structure. Of course the rollers 11 should have considerable clearance with respect to the pivot bolts 12 to permit the trunnion extensions to pass the rollers.

5 The exterior of the drum structure serves to support a plurality of longitudinal rows of molds 14. Each of the molds is in communication with the drum interior, as illustrated for example in Fig. 8. Thus each of the molds 14 includes a pair of upright sides 15 and 16 shown as integral with the transverse bosses 17. These bosses 17 extend not only beyond the sides 15 and 16, but also between these sides, as shown in Figs. 8 and 9. The exterior portions of the boss 17 serve to accommodate the fastening means 18 by the aid of which the mold structure can be attached to the sheet metal drum portion 5. These upright portions 15 and 16 form the end walls of the mold structure. One side wall of the mold structure may be formed by a member 19 which is inserted between the upright walls 15 and 16 and which may be held in place therein as by the aid of the through bolts 20. This side wall 19 may also be provided with a flange 21 forming with the flange 17 a converging gate opening 22 leading upwardly into the mold space and communicating with the aperture 23 formed in the member 5. Each of the molds 14 thus is in alignment with one aperture 23, a number of which are shown in Fig. 3. Through these apertures and the converging gate opening 22, the plastic material may flow radially outwardly into the mold space 24, under the influence of centrifugal force.

35 Forming the other side wall of the mold structure is a movable member 25. This movable member 25 is shown removed from the mold in Fig. 11. It is shown in closed position in Fig. 8 and in open position in Fig. 12. This side wall member 25 is provided with a cylindrical projection 26 at its lower end by the aid of which it may be journaled in a cylindrical groove 27 (Fig. 11) formed near the inner edge of the boss 17 between the upright ends 15 and 16. In closed position the surface 28 of member 25 is in contact with the overhanging lip 29 of the side member 19, forming the closed mold space 24. During the process of casting, the gate opening 22 is opened and the member 25 is closed as illustrated in Fig. 8. When it is desired to discharge the cast article, the member 25 is opened to the position shown in Fig. 12.

40 In order to accomplish this opening and closing movement, the member 25 is provided with an integral ear 30. This ear, as shown most clearly in Figs. 9 and 10, serves to support a pivot bolt 31 for a connecting link 32. This connecting link is connected at its free end to a clevis lever 33 attached to a shaft 34 for operating the lever 33. It is apparent that when shaft 34 is rotated in a counterclockwise direction as viewed in Fig. 9, the member 25 is urged toward opening position; and when the shaft 34 is rotated in a clockwise direction, the member 25 is urged toward closing position. It is also to be noted that the cylinder socket 27 in conjunction with the link 32 and lever 33 constrains the motion of member 25 as a pivotal one about the axis of the center of the cylindrical projection 26.

45 The shaft 34 can extend longitudinally along the drum so that it coacts with all of the molds 14 in a common row, there being as many such shafts 34 as there are rows of molds. This is shown clearly in Fig. 3. The manner in which

the shaft 34 is rocked to open and close the mold will be described hereinafter.

50 Before the mold structure 14 is opened, the gate opening 22 should be closed. The gate opening closure in the present instances is shown as 5 consisting of a flat plate 35. This flat plate 35 has a slanting advancing edge which progresses across the bottom of the mold space 24. It is guided for its opening and closing movements partially in an appropriate slot formed in the 10 bottom of the member 19 and also by the aid of a guide plate 36 (Fig. 7). This guide plate 36 forms with the flange 21 a guide groove for the gate closure 35 and is fastened to the flange 21 as by the aid of the bolts 37. In order that the 15 closure member 35 may pass the bolts 37, this closure member can be provided with slots 38 as shown in Fig. 11.

15 The advancing edge of the gate closure 35 is adapted to cooperate with the bottom portion of 20 the movable wall 25 as illustrated in Fig. 12. Its reciprocating motion to open and close the bottom of the mold and thereby to control the ingress of plastic material into the mold includes a shaft 39. This shaft 39 as shown in Fig. 3, can 25 extend across all of the mold structures 14 in a common wall so that all of the closures 35 for all of the molds in a row are operated at once. The operating connection can comprise a lever 40 fastened to the shaft 39 and having a knob 41 30 engaging inside of an aperture in the gate 35. Guide plate 36, as shown in Fig. 7, is appropriately slotted to permit the passage of this part of the lever 40.

35 As shown most clearly in Fig. 8, a counter-clockwise rocking of shaft 39 will serve to close the gate opening. In order to open the gate from the closed position of Fig. 12, a clockwise rotation of shaft 39 is necessary.

40 Auxiliary devices for forming nail openings in the shingle 1 during the process of casting are also illustrated. Thus for example, these cores can be in the form of bars 42 which are adapted to be extended transversely across the mold space 24 and to contact with the inner surface of the 45 movable mold member 25. These bars 42 form the spaced nail openings 43 (Fig. 13). They are withdrawn at the same time that the mold is opened. This is accomplished, for example, by providing a socket member 44 on the end of each 50 bar 42. In this socket member is disposed the operating end of a lever 45 also fastened to the shaft 34. Accordingly it is seen that simultaneously with the opening of the mold 14, the core bars 42 are also withdrawn to the position shown 55 in Fig. 12.

45 An additional lever 46 may also be provided for operating a plunger 47 to free the article 1 from the mold. This plunger 47 may also be provided with a head 48 formed as a socket for 60 the accommodation of the operating end of lever 46.

50 The arrangement is such that an operator can at will, cause the molds 14 to open as they pass a stationary mechanism. This is illustrated to 65 best advantage in Figs. 1, 3, 4 and 5.

55 Thus attached to each of the shafts 34 at one end thereof there is a lever 49. This lever carries at its free end a cam follower roller 50. It is apparent that a rotation of lever 49 in a clockwise direction as viewed in Fig. 1, will serve to open the molds in the associated row. The mold 14, illustrated as being in a horizontal position, is ready to be opened in this manner.

60 This opening is accomplished by the aid of a 75

cam track mechanism which coacts with the followers 50 as the rotation of the drum 5 progresses. This cam track is formed of an arcuate section 51 integral with a flange 52 of arcuate form. This flange 52 is appropriately supported upon the support 9. The integral track 51 is supplemented by a swinging cam section 53, which can be swung outwardly to the position illustrated in Fig. 1, or inwardly to assume the position shown in dotted lines in Fig. 1. This movable cam section 53 can be journaled in an arcuate socket in the end of cam section 51 as illustrated in Fig. 4. Flange 52 can also be provided with a circular recess 54 in which the circular boss 55 attached to the movable cam section 53, is accommodated. In this way the angular motion of the cam section 53 is provided for. If desired, a pivot pin 56 may extend through the boss 55 and between the two cam sections 51 and 53.

The free end of the adjustable cam section 53 is provided with opposed sloping faces 57 and 58. When moved outwardly to the position of Fig. 1, the cam followers 50 contact with the sloping face 57 and upon continued rotation of the drum structure, the cam followers 50 are urged to follow the inner surface of the stationary cam section 51. This condition is illustrated in Fig. 1 by those followers 50 which are associated with the mold structures 14 that have passed the horizontal positions. These molds 14 are therefore in opened position. The articles 1 are then free to drop out of the molds both by gravity and by centrifugal force onto a conveyor belt 59 provided at the bottom of the drum.

If, on the other hand, it be desired to close molds 14 as they pass through the horizontal position, the movable cam section 53 is urged inwardly to the dotted line position of Fig. 1. In this position the cam followers 50 engage the sloping surface 58 of the movable cam 21 and are urged outwardly to ride on the outer surface of the stationary track section 51. This causes a rotation of the shafts 34 in a counterclockwise direction as viewed in Fig. 1 to return the mold to closed position.

The optional positioning of the movable cam section 53 is accomplished in any appropriate manner. Thus, for example, the movable cam section 53 can be joined to a link 60 as by the aid of a right angled extension 61 which passes through a slot 62 in the flange 52. The free end of the link 60 is joined as by the aid of a clevis 63 to a lever 64. This lever 64 is formed integral with a hand control lever 65 pivoted by the aid of a pin 66. By rotating the hand lever 65 in a clockwise direction from the position of Fig. 1, the cam section 53 can be moved inwardly. In order to hold the cam section 53 in either of its adjusted positions, the usual segment and catch mechanism can be provided. The segment 67 is shown as formed integrally with a horizontal extension of the flange 52. The catch 68 is shown as operated by the lever 69 pivoted below the handle 70 of the lever 65.

It is apparent that a clockwise rotation of shaft 34 is accomplished during rotation of the rotary drum, and it is unnecessary to stop the mechanism to discharge the article 1 from the mold 14.

It is also apparent that shaft 39 may be similarly controlled by a cam and follower mechanism arranged at that end of the drum 5 which is opposite to the end hand lever 65 is located. Thus for example, at that end there is a seg-

ment 71 appropriately supported on the support 9. This segment 71 carries an integral cam track 72. An adjustable cam section 73 (Fig. 6) is arranged to be moved to either its full line position or its dotted line position of Fig. 2. For this purpose section 73 has a circular end cooperating with a circular groove in the contiguous end of the integral track 72. It is also provided with an integrally formed shaft 74 passing through the hub 75 formed on the segment 71. Attached to this shaft 74 for adjusting the position of the section 73 is a lever 76 joined as by a link 77 to a clevis 78. This clevis in turn is joined to the lever 79 fastened to the shaft 66 to which the hand lever 65 is fastened. Thus it is apparent that operation of the hand lever 65 will cause an operation of the cam section 73, as well as of the cam section 53. However, the operation is in different directions; that is, the section 73 is urged inwardly when section 53 is urged outwardly. This opposite motion is for the purpose of rotating the shaft 39 in an opposite direction required for moving the gate closure 35 as heretofore explained when the cam followers 80 carried on the lever 81 contact therewith. The levers 81 are fastened to the shaft 39. As they pass through the horizontal position of Fig. 2, the shafts 39 are given a counterclockwise rotation causing the gate closures 35 to close. On the other hand, if the cam section 73 is placed in the dotted line position of Fig. 2, the cam followers 80 will be urged to move along the inner surface of the stationary track 72, and shafts 39 are rotated in a clockwise direction for opening the gate closure 35.

It is also to be noted that the angular extent of segment 71 is greater than the angular extent of the segment 52. In this way it is ensured that the gates 35 will be closed before the molds 14 open; on the other hand, when the lever 65 is moved so as to close the molds, the gate closures 35 will be opened before molds are closed.

The mode of operation of the mechanism is apparent from the foregoing. The hand lever 65 is first set to move the cam section 53 to mold closing position and the cam section 73 to gate opening position. The molds then assume the position of Fig. 8, the core bars 42 being inserted into the mold space. The molds 14 will then assume the position of Fig. 8. Upon rotation of the drum 5, the plastic material is poured into the drum interior through either of its trunnions. Centrifugal force urges the plastic material compactly into the mold spaces 24 and excess moisture is pressed out and a homogeneous product is ensured. Upon sufficient rotation of the drum, the lever 65 is set to the position of Fig. 1, the molds then opening and the gates 35 closing, the position of the molds 14 being indicated in Fig. 12. Thereupon centrifugal force, as well as gravity serves to deposit the articles upon the moving conveyor 58 from which they can be removed and stacked.

What is claimed is:

1. In centrifugal casting apparatus, a rotary member, a series of molds carried by the member, and means for optionally causing the molds to open during rotation of the member, and for causing the mold to stay closed for any desired number of revolutions.

2. In centrifugal casting apparatus, a rotary member, a series of molds carried by the member, each of said molds having a movable part to permit its opening, and means for optionally operating said part while the member is rotating.

and for causing the mold to stay closed for any desired number of revolutions.

3. In centrifugal casting apparatus, a rotary member, a series of molds carried by the member, and means optionally causing the molds to open or to close, during rotation of the member, and for causing the mold to stay closed for any desired number of revolutions.

4. In centrifugal casting apparatus, a rotary member, a series of molds carried by the member, means forming gate closures between the molds and the member, and means for causing the molds to open and the gate closures to close during rotation of the member.

15 5. In centrifugal casting apparatus, a rotary member, a series of molds carried by the member, means forming gate closures between the molds and the member, means causing the molds to open for discharging the cast articles, and 20 means for operating the mold opening means and the gate closures during rotation of said member.

6. In a centrifugal casting apparatus, a rotary material receiving member, a series of molds supported on the member and adapted to receive the material therefrom, and capable of opening to facilitate discharge of the contents of the mold, and means for causing said mold to open so that 25 centrifugal force may be utilized to aid the discharge of the mold contents.

30 7. In a centrifugal casting apparatus, a rotary material receiving member, a series of molds supported on the member and adapted to receive the material therefrom, and capable of opening to facilitate discharge of the contents of the mold, a cam and follower mechanism for operating the molds during rotation of the member, and means 35 for adjusting the same optionally to cause the molds to open or to close.

40 8. In a centrifugal casting apparatus, a rotary material receiving member, a series of molds supported on the member and adapted to receive the material therefrom, means forming gate closures between the member and the molds, a cam and follower mechanism for operating the gate 45 closures during rotation of the member, and means for adjusting the cam optionally to cause the gate closures to open or to close.

45 9. In a centrifugal casting apparatus, a rotary drum into which plastic material may be introduced, a series of rows of molds supported on the drum exterior and adapted to be placed in communication with the interior of the drum, each of 50 said molds having a movable part so that the mold may be opened to discharge the cast article, and means for optionally causing the molds in a row to open when the row reaches a definite angular position.

55 10. In a centrifugal casting apparatus, a rotary drum into which plastic material may be introduced, a series of rows of molds supported on the drum exterior and adapted to be placed in communication with the interior of the drum, each of said molds having a movable part so that 60 the mold may be opened to discharge the cast article, and means for optionally causing the molds in a row to open or to close when the row reaches a definite angular position.

11. In a centrifugal casting apparatus, a rotary drum into which plastic material may be introduced, a series of rows of molds supported on the drum exterior and adapted to be placed in communication with the interior of the drum, each of 5 said molds having a movable part so that the mold may be opened to discharge the cast article, and means for optionally causing the molds in a row to close when the row reaches a definite angular position.

10 12. In a centrifugal casting apparatus, a rotary drum into which plastic material may be introduced, a series of rows of molds supported on the drum exterior and adapted to be placed in communication with the interior of the drum, 15 gate closures for controlling communication between the drum and the molds, and means for optionally causing the gate closures for the molds in a row to close when the row reaches a definite angular position.

20 13. In a centrifugal casting apparatus, a rotary drum into which plastic material may be introduced, a series of rows of molds supported on the drum exterior and adapted to be placed in communication with the interior of the drum, gate 25 closures for controlling communication between the drum and the molds, and means for optionally causing the gate closures for the molds in a row to close or to open when the row reaches a definite angular position.

30 14. In a centrifugal casting apparatus, a rotary drum into which plastic material may be introduced, a series of rows of molds supported on the drum exterior and adapted to be placed in communication with the interior of the drum, gate 35 closures for controlling communication between the drum and the molds, and means for optionally causing the gate closures for the molds in a row to open when the row reaches a definite angular position.

40 15. In a centrifugal casting apparatus, a rotary drum into which plastic material may be introduced, a series of rows of molds supported on the drum exterior and adapted to be placed in communication with the interior of the drum, each of 45 said molds having a movable part so that the mold may be opened to discharge the cast article, and means for optionally causing the molds in a row to open when the row reaches a definite angular position, comprising a cam and follower 50 mechanism, and means for adjusting the position of the cam.

55 16. In a centrifugal casting apparatus, a rotary drum into which plastic material may be introduced, a series of rows of molds supported on the drum exterior and adapted to be placed in communication with the interior of the drum, gate closures for controlling communication between the drum and the molds, and means for optionally 60 causing the gate closures for the molds in a row to close when the row reaches a definite angular position, comprising a cam and follower mechanism, and means for adjusting the position of the cam.

ALBERT E. MOORHEAD. 65
